UNITED STATES PATENT OFFICE

136,967

DESIGN FOR A TOY GUN

Louis G. Balantyne, Chicago, Ill.

Application November 17, 1943, Serial No. 111,706

Term of patent 7 years

To all whom it may concern:

Be it known that I, Louis G. Balantyne, a citizen of the United States, residing at Chicago, in the county of Cook and State of Illinois, have invented a new, original, and ornamental Design for a Toy Gun, of which the following is a specification, reference being had to the accompanying drawing, forming part thereof.

Figs. 2 and 3 are side and front views thereof.

I claim:

The ornamental design for a toy gun, as shown.

LOUIS G. BALANTYNE.
